UNITED STATES PATENT OFFICE.

JOSHUA C. JONES, OF WILKES-BARRE, PENNSYLVANIA.

CAR-DERAILER.

1,116,075.

Specification of Letters Patent. Patented Nov. 3, 1914.

Application filed June 12, 1913. Serial No. 773,287.

To all whom it may concern:

Be it known that I, JOSHUA C. JONES, a citizen of the United States, residing at Wilkes-Barre, in the county of Luzerne and State of Pennsylvania, have invented a new and useful Car-Derailer, of which the following is a specification.

The present invention relates to improvements in car derailers, one object of the invention, being the provision of a derailer which will derail a car moving in one direction, but which will be ineffective as a derailer when the car is moved in the opposite direction.

A further object of the present invention, is the provision of means for moving a derailer into derailing position and for locking the same in such position, the locking device being automatically released when the derailer is placed in inoperative position.

With the foregoing and other objects in view which will appear as the description proceeds, the invention resides in the combination and arrangement of parts and in the details of construction hereinafter described and claimed, it being understood that changes in the precise embodiment of the invention herein disclosed can be made without departing from the spirit of the invention.

In the drawings—Figure 1 is an end elevation of the derailer showing a rail in cross section. Fig. 2 is a similar view with the derailing member in derailing position. Fig. 3 is a side elevation taken from the opposite side of the device. Fig. 4 is a top plan view thereof. Fig. 5 is a cross section taken on line 5—5 of Fig. 4.

Referring to the drawings, the numeral 1 designates the rail, which has placed therebelow the two plates 2, said plates 2 being provided each with a pair of attaching and limiting lugs 3 for engagement with the tie

4. Formed integral with the plates 2 are the two upstanding braces 5, which are connected together by and support the curved web 6, and the rail engaging member 7, said rail engaging member being disposed and formed to fit the base and web of the rail and provide a segmental cavity 8 for the sliding reception of the movable derailing member 9. This derailing member 9 is so disposed as to assume the two positions, as shown in Figs. 1 and 2, the same when in the position in Fig. 1 being in normal out-of-

way position, while as shown in Fig. 2 it is in a position for derailing the car. The derailing member 9 is provided with the oppositely extending lugs 10, which coact with the adjacent portion 7' of the supporting member to limit the downward movement thereof, as clearly illustrated in Fig. 1.

In order to properly oscillate the derailing member 9, the same is provided with the lug 11, which has operably connected thereto, the operating rod 12, whose outer end 13 is adapted to be connected with any switch mechanism so that when the switch is in a position to properly operate the derailer, the rod 12 is pulled upon and consequently moves the derailing member 9 from the position in Fig. 1 to that shown in Fig. 2.

In order to provide a means for locking the derailing member in the position, as shown in Fig. 2, the same being locked coincident with the movement of the same to such position, a pin 14, carried by the rod 12, is in the path to engage the lower over-balancing and free end of the locking member or latch 15, which is pivoted at 16 so that its upper end is projected through a slot in the web 6 to fit in the socket or depression 17 of the derailing member 9. The parts are in the proper locked position, as shown in Fig. 2, with the upper edge of the depression 17 out of contact or spaced from the upper end of the latch 15, sufficiently far to permit the latch 15, when its lower end is primarily released by the pin 14, as the rod 12 is pushed to the right in Fig. 2, to start the movement of the member 9 from derailing position, the weight of the lower free end of the latch 15 will then cause it to assume the vertical position, as in Fig. 1, so that the member 9 is fully released and can be moved to the position, as shown in Fig. 1.

It is apparent that when the lever 12 is moved from the position shown in Fig. 2 to that shown in Fig. 1, that the lower end of the locking member 15 being released, will permit the removal of the upper end from the recess 17 and thus permit the movement of the derailing member 9, from the position shown in Fig. 2 to that shown in Fig. 1.

The upper end of the derailing member 9 is provided with the head 18, having the tapered projecting ends 19, which when the member is in the position as shown in Figs. 2 and 3, rests upon the tread of the rail 1, and thus provides a proper guiding means for the rim of the car wheel, such car wheel

when moving from left to right in Fig. 4, passing into the entering end 20 of the inclined flange receiving groove 21, so that the flange will cause the wheel thereof to be derailed and pass upon the outer surface of the rail 1.

In order to provide a means to prevent the derailing of a car should the same move from left to right in Fig. 4, when the derailing member is in derailing position, a flange receiving groove 22 is provided so that when the tread of the rim of the wheel rides upon the head 18, the flange will enter the groove 22 and thus be properly guided over the head of the derailer without being deflected from the rail.

From the foregoing description, taken in connection with the drawings, it is evident that with a derailer constructed according to the present invention, that the same may be readily applied at the desired point of the track, and operably connected to the switch and signaling mechanism, so that the operation of moving the same from its normal out-of-use position, as shown in Fig. 1, to the derailing position, in Fig. 2, will be coincident with the operation of the switch point and signaling mechanism so that an additional safeguard will be provided, and an approaching train will be purposely derailed, while should the derailing device be inoperative, the protected train if passed thereover will not be derailed due to the flange recess or groove 22 of the present device.

What is claimed is:

1. A derailer, including a base, an open segmental casing carried thereby, a segmental plate mounted in said casing for oscillatory movement, said plate being provided with a wheel flange guide for disposition above and in contact with the rail when the plate is in derailing position, means for oscillating the plate, and means for holding the plate in derailing position.
2. A derailer, including a base, an open segmental casing carried thereby, a segmental plate mounted in said casing for oscillatory movement, said plate being provided with a wheel flange guide for disposition above and in contact with the rail when the plate is in derailing position, means for oscillating the plate, and means for holding the plate in derailing position.

tal plate mounted in said casing for oscillatory movement, said plate being provided with a wheel flange guide for disposition above and in contact with the rail when the plate is in derailing position, means for oscillating the plate, means for holding the plate in derailing position, and means for oscillating the plate for actuating the holding means.

3. A derailer, including a base, an open segmental casing carried thereby, a segmental plate mounted in said casing for oscillatory movement, said plate being provided with a wheel flange guide for disposition above and in contact with the rail when in derailing position, a rod connected to the plate for oscillating the same, co-operative locking means carried by the plate and disposed in the path thereof for holding the plate in derailing position, and means carried by the rod for placing one of said means in locking position.

4. A derailer, including a base, an open segmental casing carried thereby, a segmental plate mounted in the casing for oscillatory movement, said plate being provided with a wheel flange guide for disposition above and in contact with the rail when the plate is in derailing position, said plate being provided with a recess in one face thereof, a rod connected to the plate for oscillating the same, a pivoted locking bar connected to the base and having one end disposed to fit in the recess of the plate to lock the plate in derailing position, and means carried by the rod for engaging the other free end of the bar to move the same into locking position when the plate is moved into derailing position.

In testimony that I claim the foregoing as my own, I have hereto affixed my signature in the presence of two witnesses.

JOSHUA C. JONES.
